UNITED STATES PATENT OFFICE.

ALDEN M. DRAKE, OF GREENFIELD, MASSACHUSETTS, ASSIGNOR TO GREENFIELD TAP & DIE CORPORATION, OF GREENFIELD, MASSACHUSETTS, A CORPORATION OF MASSACHUSETTS.

WHEEL-TRUING DEVICE.

Application filed March 8, 1926. Serial No. 93,001.

This invention relates to a device for truing the face of a grinding wheel and for providing an accurate cylindrical surface thereon. It is designed to form part of the permanent structure of a type of grinding machine in which accurate facing of the wheel is of great importance.

An important feature of my invention relates to the provision of a strong and rigid support for a diamond point or other wheel dressing tool by which the tool will be firmly supported for movement axially of the machine. Another feature of my improved construction is the provision of a radially adjustable support for said tool, said support being of an improved form and preferably including a wheel guard formed as an integral part thereof.

My invention further relates to arrangements and combinations of parts which will be hereinafter described and more particularly pointed out in the appended claims.

A preferred form of the invention is shown in the drawings in which Fig. 1 is a front elevation of a portion of a grinding machine having my improved truing device embodied therein;

Fig. 2 is a sectional front elevation of the truing device;

Fig. 3 is an end view thereof, looking in the direction of the arrow 3 in Fig. 1;

Fig. 4 is a detail sectional plan view, taken along the line 4—4 in Fig. 3; and

Fig. 5 is sectional end elevation, taken along the line 5—5 in Fig. 2.

Referring to the drawings, I have shown a grinding wheel W mounted on a shaft or spindle 10 rotatable in a wheel shaft bearing member 11, slideable axially upon or secured to a wheel carriage 11^a, which in turn is slideable transversely on a grinding machine frame 12.

These parts in themselves form no part of my present invention which relates more particularly to an improved truing device to be now described.

My improved truing device comprises a supporting member 13 which is preferably tubular and of relatively large diameter and heavy construction, so that the wheel dressing tool supported thereon will be held with great rigidity. The member 13 is slideable in a bearing block or head 15 through which it extends. A casing or cover 16 may be secured to the head 15 to enclose and pro-

tect the rear end of the supporting member 13 as the truing device is moved toward the bearing head.

A rack bar 17 is secured to the side of the member 13 and fits within a corresponding recess in the head 15, as indicated in Fig. 5. The rack bar thus acts as a guide for the member 13, preventing angular displacement thereof. A pinion 18 on a shaft 19 engages the rack bar 17 for moving the member 13 axially. The shaft 19 is mounted in a bearing in the head 15 and is provided with a hand wheel 20 for rotation thereof. The member 13 is thus very firmly and rigidly supported in the bearing head 15 which is preferably secured by bolts 22 to the wheel shaft bearing member 11.

A tool head 24 (Fig. 4) is mounted in guide-ways 25 on the end of the member 13 for vertical sliding movement thereon and may be secured in adjusted position by clamping screws 26. This provides for a rough or approximate adjustment of the wheel dressing tool, which is preferably formed as a diamond point 30 (Fig. 2) secured to the lower end of a plunger 31 slideable in a recess 32 in a head 24.

An adjusting screw 33 is provided for accurate adjustment of the wheel dressing tool 30 in the head 24 and a screw or stud 34 (Fig. 4) engages a slot or keyway in the plunger 31 and prevents angular displacement thereof. The lower end of the head 24 is provided with a lateral segmental projection 40 which acts as a wheel guard during the truing operation and also protects the diamond point from accidental injury.

Having described the construction of my improved wheel truing device, it will be seen that the device is particularly noteworthy for the firm and rigid construction of the supporting member and for the simplicity of all parts associated therewith. The member 13 is mounted in accurate parallel relation to the wheel shaft or spindle 10, so that the diamond point 30 when moved axially by the hand wheel 20 will dress the wheel W to accurate cylindrical form. The diamond point may be fed downward as needed by the adjusting screw 33 and the device may be adapted to wheels of different diameter by loosening the clamping screws 26 and raising or lowering the head 24 on the member 13.

Having thus described my invention and

the advantages thereof, I do not wish to be limited to the details herein disclosed otherwise than as set forth in the claims, but what I claim is:

- 5 1. In a grinding machine having a wheel carriage, a wheel, a wheel shaft, and a wheel shaft bearing member mounted on said carriage, a wheel dressing tool, a heavy rigid supporting member for said tool, a bearing head for said supporting member mounted on said carriage adjacent said wheel shaft bearing member and in which said supporting member is constantly guided for movement parallel to and axially of said wheel shaft, and manual means to move said supporting member in said bearing head.
- 10 2. In a grinding machine having a wheel carriage, a wheel, a wheel shaft, and a wheel shaft bearing member mounted on said carriage, a wheel dressing tool, a heavy rigid supporting member for said tool, a bearing head for said supporting member mounted on said carriage and in which said supporting member is constantly guided for movement parallel to and axially of said wheel shaft, a rack bar secured to said supporting member, and a manually operable pinion engaging said rack bar and effective to move said wheel dressing tool across the grinding 30 wheel.
- 15 3. In a grinding machine having a wheel carriage, a wheel, a wheel shaft, and a wheel shaft bearing member mounted on said carriage, a wheel dressing tool, a heavy rigid supporting member of circular section for said tool, a bearing head for said supporting member mounted on said carriage and in which said supporting member is guided for movement parallel to and axially of said wheel shaft, a rack bar secured to said supporting member and effective to prevent angular displacement thereof, and a pinion engaging said rack bar, manual rotation of said pinion causing axial movement of said supporting member and said wheel dressing tool.
- 20 4. In a grinding machine, a frame, a wheel shaft rotatably mounted therein, a

wheel dressing tool, a hollow cylindrical tubular supporting member for said dressing tool, said member being of relatively large diameter and having a sliding bearing adjacent said wheel shaft, and means to prevent angular displacement of said supporting member.

55 5. In a grinding machine, a frame, a wheel shaft rotatably mounted therein, a wheel dressing tool, a tubular supporting member for said dressing tool, said member being slideable in a bearing adjacent said wheel shaft and in a path parallel to and axial of said wheel shaft, and a hollow casting secured to said frame and receiving and protecting the end of said supporting member when the wheel dressing tool approaches 65 the bearing of said supporting member.

6. A wheel truing device as set forth in claim 1, in which a tool head is secured to the end of said supporting member by a bolt and slot connection affording rough adjustment of said head toward and from the wheel, and in which a wheel dressing tool is slidably mounted in said head and is also independently adjustable toward and from the wheel.

75 7. A wheel dressing device as set forth in claim 1, in which a tool head is secured for adjustment toward and from the wheel on the end of said supporting member, and in which said tool head has a substantially 80 segmental projection effective to act as a guard for the grinding wheel and dressing tool.

8. A wheel dressing device as set forth in claim 1, in which a tool head is secured for 85 adjustment toward and from the wheel on the end of said supporting member, and in which a wheel dressing tool is slidably mounted in said head but is held from angular movement therein, and in which an adjusting screw is provided, effective to move said wheel dressing tool in said tool head toward and from the work.

In testimony whereof I have hereunto affixed my signature.

ALDEN M. DRAKE.
